Attorney

Patented Apr. 17, 1923.

UNITED STATES PATENT OFFICE.

EARNST A. BOSTROM, OF GRIFFIN, GEORGIA, ASSIGNOR TO POMONA PRODUCTS COMPANY, OF GRIFFIN, GEORGIA, A CORPORATION OF GEORGIA.

ROASTING MACHINE.

Application filed June 18, 1921. Serial No. 478,608.

To all whom it may concern:

Be it known that I, EARNST A. BOSTROM, a citizen of the United States of America, residing at Griffin, in the county of Spalding and State of Georgia, have invented certain new and useful Improvements in Roasting Machines, of which the following is a specification, reference being had therein to the accompanying drawing.

My invention relates to means for removing the skins from vegetables and more particularly to means for removing the skin of pimento peppers by roasting or singeing.

The main object of the invention is to provide a roasting machine which will continuously and automatically carry out the roasting process on a large scale with uniform results and capable of being adjusted to bring about the results required.

Other objects of the invention will be apparent from a perusal of the following specification and drawings accompanying the same.

My invention is illustrated in the accompanying drawings in which:

Fig. 1 is a plan view of the roaster;

Fig. 2 is a side view of the roaster;

Fig. 3 is an end view of the roaster cut on the line 3—3 of Fig. 1 with the guard removed and looking in the direction of the arrows;

Fig. 4 is an enlarged sectional view of the gas furnace on the line 4—4 of Fig. 1, looking in the direction of the arrows showing the position of the gas burners, which enter alternately on opposite sides of the bottom of the furnace, as hereinafter explained;

Fig. 5 is a detail sectional enlargement of the carrier, which takes the pimentos through the furnace; and

Fig. 6 is a section taken on the line 6—6 of Fig. 5, looking downward.

The main frame 1 is fabricated from angle iron of suitable size and strength, said angles being bolted and riveted together, so as to form a strong and substantial framework for holding the gas furnace and moving parts of said machine.

A gas furnace 2 is located as shown on one side of the framework. This furnace is built up of fire brick as shown in detail section, Fig. 4, having a slot lengthwise through the furnace, for permitting the carrier rods to pass through from one end of

the furnace to the other. In practice this furnace is about fourteen feet in length, and five by seven inches in internal cross section, with gas burners entering the bottom just by the sides, and alternating first one side and then the other, about nine inches apart, forming a continuous flame the whole length of the furnace for the purpose of quickly and completely burning up the skin on said pimentos when carried through the furnace on the carriers, as hereinafter described.

For the purpose above mentioned of carrying the pimentos through the furnace, an endless chain carrier is constructed, composed of a series of cast iron frames 3 as shown in partial section, Fig. 5, having an upright rotatable shaft 4 with a pear-shaped form 5 on its upper end, for holding the pimentos, said shaft being suitably supported in frame 3 by a bearing or step at the bottom end of said shaft 4, and a bearing two-thirds of the way up as shown. Said cast iron frame 3 has a stationary pin or shaft 6 inserted at its lower end as shown, for the purpose of taking the grooved guide roller 7 which is held on to said shaft with a cotter pin as shown. The cast iron frame 3 has two (K') attachments of link belt chain bolted to same at suitable distance apart as shown, Fig. 5. These (K') attachments when linked up with two plain chain links between each frame, form the endless carrier before mentioned, the guide roller 7 resting on a track 28 extending along both sides of the machine as shown, and connecting at each end with a platform 29 suitably supported and connecting with said track so as to support and guide said rollers on to track 28.

To actuate this endless carrier, two suitable sprockets 8 are keyed on to the upright shaft 9 suitably spaced to engage the link belt chain and attachments bolted to said carrier 3 and forming the driving shaft for the carriers at the head end of the machine. A corresponding pair of sprockets is carried at the opposite end of the main frame, held in a take-up device 11 having a hand wheel nut and screw X for the purpose of keeping the chains of the carrier at the proper tension at all times.

Motion to this upright shaft 9 is derived from the jack shaft 12 carrying a bevel pinion on one end, engaging a bevel gear on

the upright shaft 9, said jack shaft 12 receiving its motion through suitable sprockets and chain, from the intermediate shaft 13, which in turn receives its motion from the 5 variable speed shaft 14, carrying a friction disc 21 at one end engaging a friction pulley 15 on high speed driving shaft 16, which carries the tight and loose driving pulleys 17 and 18. A variable speed is obtained 10 by turning hand wheel 19 which through worm 20 moves friction pulley 15 out or in on friction disc 21.

Intermediate shaft 13 extends to foot or opposite end of the machine. At this end 15 of the shaft 13 it carries a sprocket 22, which through a suitable sprocket chain and gears revolves the brush shaft 23, which serves the purpose of removing the pimentos from the carrier as shown at 24.

20 The operation of the roaster is as follows: The gas and air pipes are first connected with the proper gas and air supply as shown in Fig. 2, the flame being adjusted in the furnace by the regulating valves 26 and 27 provided as shown. Motion is then given the carriers by shifting the drive belt on to the tight pulley 17, which starts the carrier chain moving. The pimentos having had the seed core removed, are placed on 25 the carriers at the foot of the machine as shown at 25 in Fig. 2, and are then moved into the furnace fire by the carriers. The intense heat puffs the skin away from the meat or body of the pimento, and is burned 30 into a smut or completely destroyed by the hot fire. The speed or time required for the destruction of the skin, is regulated by the hand wheel 19 as is also the intensity of the fire by the valves 26 and 27. After passing 35 through the furnace, the pimentos are gradually cooled off by the time they reach brush 23 when the revolution of brush 23 removes them and they drop into the box or receptacle as shown at 24, from whence the 40 pimentos go to the washer to have the burned skin washed off.

I claim:

1. A roasting machine having a combination of a gas furnace, a carrier chain for 45 conducting pimentos through the furnace, a rotating brush for removing the pimentos

from the carriers, and a regulating device for controlling the speed of said carriers, substantially as set forth.

2. A roasting machine for the purpose described comprising a roasting chamber, an endless chain of carriers arranged to be driven through said chamber, each of said carriers comprising a vertically arranged rotatable shaft having a holder adapted to fit into and support a pimento pepper against lateral and downward displacement, and driven means outside of said roasting chamber for removing the pimento pepper upwardly from off said holders.

3. A roasting machine comprising a furnace open at the bottom and ends, means for introducing gas for combustion in said furnace from beneath and in an upward direction, and carrier elements traveling through 70 said furnace with means for supporting same from beneath.

4. A roasting machine comprising a furnace having continuous side walls and open arch, an opening extending the length of 75 the furnace in the bottom part thereof, a carrier traveling beneath said opening, means on said carrier extending into the furnace for supporting fruit or vegetables therein, and means to supply gas for combustion in said furnace along the side walls in an upward direction.

5. In a roasting machine for peeling fruit, a singeing furnace, a fruit carrier for carrying fruit therethrough, driving means for 85 said carrier and means for regulating the speed of said carrier independently of said driving means.

6. In a roasting machine for peeling fruit, the combination of an elongated furnace, 90 fruit conveying mechanism mounted below and outside the walls of said furnace, and fruit carriers extending from said conveying mechanism into the furnace, said extension carriers having no relatively moving 95 parts.

In testimony whereof I affix my signature.

EARNST A. BOSTROM.
